UNITED STATES PATENT OFFICE.

ISAAC E. PALMER, OF MIDDLETOWN, CONNECTICUT.

DESIGN FOR A HAMMOCK.

SPECIFICATION forming part of Design No. 34,043, dated February 5, 1901.

Application filed January 10, 1901. Serial No. 42,813. Term of patent 14 years.

To all whom it may concern:

Be it known that I, ISAAC E. PALMER, a citizen of the United States, and a resident of Middletown, in the county of Middlesex and State of Connecticut, have invented and produced a new and original Design for a Hammock, of which the following is a specification.

The essential feature of my design consists in a hammock having a marginal stripe composed of a series of skeleton squares.

The accompanying drawing represents the body of the hammock in top plan.

The body of the hammock is represented as

a whole by *a* and the squares which compose the marginal stripe by *b*.

What I claim is—

The design for a hammock, substantially as herein shown and described.

In testimony that I claim the foregoing as my invention I have signed my name, in presence of two witnesses, this 27th day of December, 1900.

ISAAC E. PALMER.
